(57) **CLAIM**

The ornamental design for a projector screen as shown and described.

DESCRIPTION

FIG. 1 is a first perspective view of a projector screen showing my new design;

FIG. 2 is a second perspective view thereof;

FIG. 3 is a front view thereof;

FIG. 4 is a rear view thereof;

FIG. 5 is a left side elevational view thereof;

FIG. 6 is a right side elevational view thereof;

FIG. 7 is a top view thereof;

FIG. 8 is a bottom view thereof;

FIG. 9 is a perspective showing a closed status thereof;

FIG. 10 is an enlarged view of portion 10 shown in FIG. 1;

FIG. 11 is an enlarged view of portion 11 shown in FIG. 1;

FIG. 12 is an enlarged view of portion 12 shown in FIG. 1;

FIG. 13 is an enlarged view of portion 13 shown in FIG. 2;

FIG. 14 is an enlarged view of portion 14 shown in FIG. 4; and,

FIG. 15 is an enlarged view of portion 15 shown in FIG. 5.

The broken lines shown in the drawings FIGS. 10-14 show unclaimed portions of the projector screen and form part of the claimed design. The dot dash lines represent a boundary for the purposes of disclosing areas of enlargement and form no part of the claimed design.

1 Claim, 15 Drawing Sheets
